CLAIM

The ornamental design for a label assembly, as shown and described.

DESCRIPTION

FIG. 1 is a front right top perspective view of a label assembly, showing our new design;

FIG. 2 is a back right top perspective thereof;

FIG. 3 is a front view thereof;

FIG. 4 is a back view thereof;

FIG. 5 is a top view thereof;

FIG. 6 is a bottom view thereof;

FIG. 7 is a left side view thereof; and,

FIG. 8 is a right side view thereof.

The evenly dashed broken lines in the drawings show portions of the article that form no part of the claimed design. The dot-dash broken lines define the bounds of the claimed design and form no part thereof.
